Specification for Design.

Patented Nov. 1, 1921.

Application filed March 31, 1920. Serial No. 370,354. Term of patent 3½ years.

To all whom it may concern:

Be it known that I, PAUL CASPARY, a citizen of the United States, residing at Chicago, in the county of Cook and State of Illinois, have invented a new, original, and ornamental Design for Buttons, of which the following is a specification, reference being had to the accompanying drawing, forming a part thereof.

The figure is an elevational view of a button, showing my new design.

The central indication of a given grade of

attainment, and the slogan placed in the rings surrounding the same, are merely shown to indicate an attractive arrangement of words and letters, and no claim is made to the particular words shown, apart from the other distinguishing features of the design.

I claim:

The ornamental design for a button as shown.

PAUL CASPARY.
